HIGH PRESSURE RECIPROCATING COMPRESSOR

Filed Nov. 20, 1928

UNITED STATES PATENT OFFICE

CHARLES SCHAER, OF LANGENTHAL, SWITZERLAND, ASSIGNOR TO THE FIRM: SULZER
FRÈRES SOCIÉTÉ ANONYME, OF WINTERTHUR, SWITZERLAND

HIGH PRESSURE RECIPROCATING COMPRESSOR

Application filed November 20, 1928, Serial No. 320,553, and in Switzerland December 12, 1927.

This invention relates to high pressure reciprocating compressors of the kind in which power is transmitted from the piston of a driving machine through an oscillating column of liquid to an intermediate piston which actuates the compressor piston. The invention relates more particularly to compressors of the above kind in which the intermediate piston is exposed on both sides to the action of a column of liquid so as to be moved thereby positively in both directions. The object of the invention is to improve the operation of compressors of this kind and to render their working parts more accessible.

According to the present invention the compression stroke of each compressor piston is effected by means of a liquid column actuated directly by the piston of the driving machine whilst the suction stroke of the compressor pistons is effected by means of a liquid column which couples these pistons and is actuated indirectly by the piston of the driving machine through each intermediate piston. The intermediate pistons are preferably disposed beneath the compressor pistons and the column of liquid directly actuated by the piston of the driving machine acts on those surfaces of the intermediate pistons which are remote from the compressor pistons. In addition the intermediate pistons may also be disposed at a lower level than the piston of the driving machine whilst the column of liquid indirectly actuated through the intermediate pistons may act on those surfaces of the intermediate pistons which are directed towards the compressor pistons.

The invention may be carried into effect in various ways but one construction of compressor according thereto is illustrated by way of example in the accompanying drawings in which

Figure 1 illustrates the compressor in plan, part of the apparatus being shown in cross-section,

Figure 2 shows a cross-section on the line $a-a$ in Figure 1, and

Figure 3 shows a cross-section on the line $b-b$ in Figure 1.

In the construction illustrated in the drawings the piston 5, termed the piston of the driving machine is reciprocated in the cylinder 6 through a piston rod 4, cross-head 3 and connecting rod 2 by means of a crank 1 which is driven from a source of power not shown in the drawings. From the two ends of the cylinder 6 lead U-shaped conduits 7 and 9 respectively which are enlarged at their other ends to receive intermediate pistons 8 and 10. These intermediate pistons are connected by means of couplings 12 and 14 to compressor pistons 11 and 13 respectively mounted to reciprocate within cylinders 19 and 20 as shown.

The conduit 7 and the space within the cylinder 6 to the right of the piston 5 is filled with liquid forming a column I between the pistons 5 and 8. Similarly the conduit 9 and the space within the cylinder 6 to the left of the piston 5 is also filled with liquid forming a column II between the pistons 5 and 10. In addition a third liquid column III is provided (hereinafter referred to as the coupling column) which is in communication with those surfaces of the intermediate pistons 8 and 10 which are directed towards the compressor pistons.

In order to compensate for leakages from the liquid columns I, II and III they are permanently connected through pipes 15, 16 and 17 to a pump which maintains the requisite working pressure within the columns, which may for example be 60 atmospheres in the columns I and II and 10 at 85 atmospheres in the column III.

As can be seen from the drawing the intermediate pistons 8 and 10 are disposed beneath the compressor pistons 11 and 13 and are also at a lower level than the piston 5 of this driving machine whilst the conduits 7 and 9 containing the liquid columns I and II are disposed below the intermediate pistons on which these columns act and extend obliquely with respect to the longitudinal axis of the piston rod 4 of the driving machine.

When the crank 1 rotates in the direction of the arrow 18 and the piston 5 moves to the left (arrows shown in full lines) the

liquid column II is forced into the the conduit 9 and acts on the under surface of the intermediate piston 10 thus forcing it upwards and causing the compressor piston 13 to compress the medium within the cylinder 20. At the same time the upward movement of the intermediate piston 10 causes the coupling column III to act on the upper surface of the intermediate piston 8 thus forcing it downwards and effecting the suction stroke of the compressor piston 11 within the cylinder 19. Simultaneously the liquid column I moves to fill up the right-hand end portion of the cylinder 6.

15 During the return stroke of the piston 5 (indicated in the drawing by arrows shown in dotted lines) the liquid column I is forced into the conduit 7 and acts on the under surface of the intermediate piston 8 and so effects the compression stroke of the piston 11. At the same time the intermediate piston 10 is forced downwards under the action of the liquid column III and effects the suction stroke within the compressor cylinder 19.

In contrast to the method of construction, in which the intermediate pistons, although acted upon on both sides by a liquid column, are driven indirectly, that is to say through two columns, by the piston of the driving machine, the invention has the advantage of eliminating during the compression stroke a further sensitive element, namely the coupling column III. 35 Further since in the compressor according to the invention the coupling column is only used to effect the suction stroke of the compressor pistons it need only be maintained at a relatively low pressure, so that the 40 power consumption of the auxiliary apparatus for supplying additional liquid to the column III to compensate for leakages is reduced.

A further advantage is obtained by means 45 of the invention since the disposition and arrangement of the liquid columns between the various pistons is such that all parts of the machine are easily accessible and those parts which are particularly subjected to wear can be readily removed and replaced.

I claim:

1. Apparatus of the class described comprising, a primary cylinder, a primary piston within the primary cylinder, two secondary cylinders, a secondary piston within each secondary cylinder, conduits connecting each end of the primary cylinder with an end of each of the secondary cylinders and the opposite ends of the secondary cylinders with each other, liquid filling the space in the conduits and the primary and the secondary cylinders, and means for reciprocating the primary piston whereby motion is transmitted from the primary piston to the 60 secondary pistons through the liquid.

2. Apparatus of the class described comprising, a primary cylinder, a primary piston within the primary cylinder, two intermediate cylinders, an intermediate piston within each intermediate cylinder, two compressor cylinders, a compressor piston connected to each intermediate piston and mounted within each compressor cylinder, conduits connecting each end of the primary cylinder with an end of each of the intermediate cylinders, and the opposite ends of the intermediate cylinders with each other, liquid filling the spaces in the conduit, in the primary cylinder and in the intermediate cylinders, and means for reciprocating the primary piston, whereby motion is transmitted from the primary piston to the intermediate pistons through the liquid.

3. Apparatus of the class described comprising, a horizontally arranged primary cylinder, a primary piston within the primary cylinder, two vertically arranged intermediate cylinders, an intermediate piston within each intermediate cylinder, two compressor cylinders, a compressor piston connected to each intermediate piston and mounted within each compressor cylinder, conduits connecting each end of the primary cylinder with an end of each of the intermediate cylinders and the opposite ends of the intermediate cylinders with each other, liquid filling the spaces in the conduits, in the primary cylinder and in the intermediate cylinders, and means for reciprocating the primary piston, whereby motion is transmitted from the primary piston to the intermediate pistons through the liquid.

4. Apparatus of the class described comprising a horizontally arranged primary cylinder, a primary piston within the primary cylinder, two vertically arranged intermediate cylinders disposed below the level of the primary cylinder, an intermediate piston within each intermediate cylinder, two compressor cylinders, a compressor piston connected to each intermediate piston and mounted within each compressor cylinder, conduits connecting each end of the primary cylinder with an end of each of the intermediate cylinders and the opposite ends of the intermediate cylinders with each other, liquid filling the spaces in the conduit, in the primary cylinder and in the intermediate cylinders, and means for reciprocating the primary piston, whereby motion is transmitted from the primary piston to the intermediate pistons through the liquid.

4. Apparatus of the class described comprising a horizontally arranged primary cylinder, a primary piston within the primary cylinder, two vertically arranged intermediate cylinders disposed below the level of the primary cylinder, an intermediate piston within each intermediate cylinder, two compressor cylinders, a compressor piston connected to each intermediate piston and mounted within each compressor cylinder, conduits connecting each end of the primary cylinder with an end of each of the intermediate cylinders and the opposite ends of the intermediate cylinders with each other, liquid filling the spaces in the conduit, in the primary cylinder and in the intermediate cylinders, and means for reciprocating the primary piston, whereby motion is transmitted from the primary piston to the intermediate pistons through the liquid.

In testimony whereof I have affixed my signature.

CHARLES SCHAER. 125
